Primary Examiner — George D Kirschbaum*Assistant Examiner* — Jennifer Watkins(74) *Attorney, Agent, or Firm* — Julie Tennyson; Marcum Tennyson PLLC(57) **CLAIM**

The ornamental design for an incontinence aid, as shown and described.

DESCRIPTION

1. Incontinence aid

Fig. 1.1 is a bottom view of an incontinence aid;

Fig. 1.2 is a top view thereof;

Fig. 1.3 is a top view thereof in a position of use;

Fig. 1.4 is a top view thereof in a folded position of use;

Fig. 1.5 is a top view thereof in an alternate folded position of use;

Fig. 1.6 is a bottom view thereof in a position of use;

Fig. 1.7 is a front view thereof;

Fig. 1.8 is a back view thereof;

Fig. 1.9 is a left view thereof;

Fig. 1.10 is a right view thereof; and

Fig. 1.11 is a perspective view in a position of use.

Incontinence aid shown in use on an adult male; the front side has expandable gathers to adjust to a variety of sizes; the bottom has an adhesive tape.

1 Claim, 11 Drawing Sheets(56)
